UNITED STATES PATENT OFFICE

116,829

DESIGN FOR AN IRRIGATING APPARATUS FOR THE HARDENING OF THE BOSOMS

René Paul, Lyon, France

Application August 11, 1938, Serial No. 79,259
In France April 22, 1938

Term of patent 7 years

To all whom it may concern:

Be it known that I, René Paul, a citizen of the French Republic, residing at Lyon, Rhone, France, have invented a new, original, and ornamental Design for an Irrigating Apparatus for the Hardening of the Bosoms, of which the following is a specification, reference being had to the accompanying drawing, forming part thereof.

Figure 1 is a bottom perspective view of an irrigating apparatus for the hardening of the bosoms, showing my design.

Figure 2 is a side elevational view thereof.

I claim:

The ornamental design for an irrigating apparatus for the hardening of the bosoms, as shown.

RENÉ PAUL.
